MORRIS GOLDMAN, OF BRIDGEPORT, CONNECTICUT

DECORATIVE LIGHTING DEVICE

Application filed April 13, 1931. Serial No. 529,642.

This invention relates to decorative lighting devices, and more particularly, to a lighting device adapted to be supported on a table, window sill, or the like, and including a row of candle-like members supporting electric lamps.

Heretofore it was proposed to provide such a device with a base for supporting candle-like members of different lengths so as to present electric lamps carried by the upper ends of the members in oppositely disposed inclined planes to enhance the decorative appearances of the lights.

Such proposals necessitated the provision of candle-like members of different lengths and required attention and effort in the selection of different length candle-like members in proper sequence to give the effect desired when making the device.

These requirements are obviated by the present invention by arranging the base so that the candle-like members are all of the same length, and yet so that they may present their electric lamps at desired heights above the base to produce the ornamental effect wanted.

This is accomplished by the present invention by providing the base with sockets for the candle-like members and placing the bottom of each socket a predetermined distance from the surface on which the base rests. Preferably, the bottoms of the sockets are at progressively increasing heights above the supporting surface proceeding from the ends of the base toward the center, so that the lamps carried by the candle-like members of uniform length will be presented in oppositely directed inclined planes.

In case the top surface of the base is flat and parallel with the supporting surface, the sockets will be of different depths with relation to the top surface of the base, but it is preferable that the sockets be all of the same depth and that the top of the base be made to follow generally a line parallel with a line through the bottoms of the sockets.

In decorative lighting devices heretofore provided, it was proposed to attach wires of each candle-like member to the lamp socket which it carries and pass these wires through

apertures in the base after which the wires were connected in series and to current supply wires in channels or otherwise at the bottom of the base.

An object of this invention is to permit the candle-like members to be wired together before being inserted in the base, and for this purpose the upper surface of the base is provided with a channel to receive wires interconnecting the adjacent lamp sockets. Preferably, these wire channels extend in a straight line through the top surface of the base and intersect the sockets in the base for the candle-like members.

An important feature resulting from the attainment of this object of the invention is the ability to use a single continuous wire from one socket to that next adjacent which runs down through the candle-like member, across the space between them, and up through the adjacent candle-like member, thus avoiding soldered or other joints in the wires interconnecting adjacent lamp sockets. If desired, the wire channel may be made deep or wide enough to receive the return wire from the lamp socket at the end of the base and carry it to the other end of the base where, with the wire attached to the socket at that end of the base, it leads to an attachment plug.

However, if desired, the return wire may be located in a groove running through the bottom of the base and, when so arranged, short-circuiting of the lamps by contact of an accidentally bared portion of the return wire with any similar portion of the lamp connecting wires, is avoided.

Other features and advantages will hereinafter appear.

In the accompanying drawings, which illustrate several forms of this invention—

Figure 1 is a front elevation of a decorative lighting device made in accordance with this invention.

Fig. 2 shows a plurality of candle-like members ready to be inserted in the base member which is shown in section.

Fig. 3 shows a plurality of candle-like members, three of which are shown in section, to indicate how, according to the present

invention, the sockets of the candle-like members may be wired before the members are placed in the base.

Figs. 4 to 8 inclusive, are side views, partly in section, of modified forms of this invention.

The lighting device of the present invention, in common with other other devices previously proposed, comprises a base 10 in the form of an elongated block having sockets 11 to receive the lower ends of tubular candle-like members 12, the upper ends of which contain sockets 13 for electric lamps 14, the sockets 11 usually being in a row extending longitudinally of the base 10. The base 10 is adapted to be supported on a flat surface such as a window sill, table, or the like, and for this purpose the bottom 15 of the base is preferably made flat, although it need not be continuous from one end to the other of the base, for the base may be cut-out as at 16, if desired.

In order that the row of lamps 14 may be presented in a line extending downwardly and outwardly from the center of the base to enhance their appearance, it was heretofore proposed to provide the tubular candle-like members of progressively increasing lengths from the ends to the center of the row of lamps. This necessitated not only the making of the candle-like members of different lengths, but required that they be kept segregated and that when assembling, they be selected and placed in proper order to give the desired appearance when assembled on the base.

To avoid this, the present invention provides the candle-like members 12 all of the same lengths and arranges the sockets 11 in the base so that the lamps 14 will be properly disposed to give the desired effect. Accordingly, the sockets 11 into which the lower ends of the tubular candle-like members 12 extend, have their bottoms 17 located in different horizontal planes with respect to the bottom 15 of the base.

When it is desired that the line of lamps 14 form a pair of oppositely directed inclined planes, as shown in Fig. 1, the sockets 11 have their bottoms 17 progressively increasing distances from the bottom 15 of the base proceeding from the ends 18 and 19 of the base toward the center 20 thereof, as shown in Figs. 2, 6, 7 and 8.

The bottoms 17 of the sockets 11 may have their distances from the base varied according to arithmetical progression as shown in Figs. 1, 2 and 6, or, they may be located in a curved plane as shown in Figs. 7 and 8, in which case the apexes of the lamps 14 define a curved line. Or, as shown in Fig. 4, the bottoms 17 of the sockets 11 may be irregularly spaced from the bottom surface 15 of the base to present the lamps 14 in a staggered line.

With regard to the base 10, it may have a flat upper surface 20 as shown in Figs. 4 and 8, in which case the depths of adjacent sockets 11 vary; or, the base may have a top surface 21 which is arcuate or curved in form, as shown in Fig. 7. However, it is considered preferable at present to have the top surface stepped in conformity with the stepped arrangement of the lamps 14, and hence, as shown in Fig. 6, the top surface 22 is provided with flat step portions, while in Fig. 1, the top surface 23 is provided with curved portions forming steps.

As stated above, it has been previously proposed, as shown in Fig. 8, to provide each lamp socket with wires 24 running down through the tubular candle-like members 12 after which the wires 24 were passed through holes 25 in the bottoms of the sockets communicating with a longitudinally extending wire passage 26 in the bottom 15 of the base. When this was done, it was necessary to solder or otherwise join, as at 27, the wires 24 from adjacent tubular members 12 with the incident use of time and labor, and these joints when left uncovered with insulation, presented a fire and shock hazard.

According to the present invention, this is avoided by providing means whereby the row of lamp sockets and candle-like members may be wired-up before being inserted in the base. As shown in Figs. 2 and 3, the lamp sockets, which each comprises a husk 28, a shell 29, and a center contact 30, are connected together in series, each one to an adjacent one by a continuous wire 31. Before the shells 29 are pressed into the husk 28 and before the husk 28 is pressed into the upper end 32 of the tubular member 12, one end of each wire 31 is soldered, or otherwise secured, to the shell 29 or center contact 30 of one lamp socket 13, while the other end of the wire 31 is soldered, or otherwise secured, to either the center contact 30 or the shell 29 of the adjacent lamp socket, the wire 31 extending down through the husk 28, then through the tubular member 12, then having a loop or free stretch 33 extending to the next adjacent tubular member 12, up through the latter and the husk 28 associated with it to the other socket contact, all without a break or joint in the wire. After this is done, the shell 29 is forced into the husk 28 and the latter is forced into the open end 32 of the tubular member 12, as shown at the right of Fig. 3.

When the lamp sockets 13 are thus connected together in a row as shown in the upper part of Fig. 2, the tubular members 12 are each pressed into one of the sockets 11 in the base. And, to accommodate the free stretches 33 or loops of wire between the adjacent tubular members 12 so as to permit the insertion of the pre-wired tubular members, the upper portion of the body 10 is provided with a longitudinally extending slot 34, intercepting or

communicating with the sockets 11, into which the free stretches 33 may be placed and retained, as shown in Fig. 1. In doing this, the assembler needs merely to guide the loops 33 to the slot 34 with his fingers, for they will be forced down to the bottom of the slot out of accessible position by the act of pressing the tubular members 12 against the bottoms 17 of the sockets in the base.

10 The wire groove 34 may be so narrow that the wire 31 just snugly fits within it, or requires the use of a flat tool to force it in if desired, and if so formed the groove will firmly retain and conceal the wire even should 15 the loop 33 be long enough to reach the surface of the base while the tubular members are driven home.

Again, the wire clearance groove 34 may be made deep enough or wide enough to accommodate 20 the return wire 35, see Figs. 2 and 3, which is connected to the socket 13 of the end of the tubular member 12, which return wire 35 is carried from the end 18 of the base to the end 19, where it meets the wire 36 attached 25 to the socket 13 at the end 19 of the base and from which point the wires 35 and 36 emerge from the end 19 of the base in the form of a cord or cable 37 having at its end an attachment plug 38 by means of which the 30 set of lamps may be connected to a convenience outlet.

It will be seen that by having each wire 31 in one continuous uninterrupted piece, there is no danger of the usually bared portion 35 thereof contacting with a similar portion of the return wire 35 which, if it occurred, would short-circuit one or more of the lamps.

If desired, the wire clearance passage 34 opening at the top of the base may contain 40 only the lamp interconnecting wires 31, and the device may be arranged as shown in Fig. 5, with a wire channel 39 provided on the bottom face 15 of the base 10 and communicating with the end socket 11 of the base 45 through a hole 40. When this is done, the return wire 35 may be brought through the hole 40, then through the channel 39 to a hole 41 at the other end of the base where it joins the wire 36 from the socket at that end. By 50 being thus isolated, any danger of short-circuiting between the wires 31 and the return wire is obviated.

With regard to the provision of the return wire channel 39, it should, of course, be understood that the arrangements disclosed in Fig. 5 may be employed in any of the other forms of the device.

Variations and modifications may be made within the scope of this invention and portions of the improvements may be used without others.

Having thus described the invention, what is claimed as new and for which it is desired to obtain Letters Patent, is:—

65 1. A decorative lighting device comprising

an elongated one-piece base having a bottom support-engaging surface, and vertical sockets open at the top of the base, said sockets having bottoms at various different distances from a line drawn through the bottom of the base; and candle-like, lamp-supporting members inserted in said sockets and supported thereby perpendicular to the bottom of the base, said candle-like members being of substantially uniform length and when resting on the bottoms of the sockets presenting electric lamps supported by their upper ends in a line conforming to and parallel with a line through the bottoms of the sockets.

2. A decorative lighting set comprising an elongated one-piece base having a bottom support-engaging surface to rest upon a flat support, and a top surface disposed at different heights along the base with reference to the bottom surface thereof; a row of vertical sockets in the base opening through the top surface thereof, said sockets being of uniform depth with relation to that portion of the top surface through which each thereof opens; and candle-like, lamp-supporting members, one inserted in each of said sockets and supported thereby perpendicular to the bottom of the base, said candle-like members being of substantially uniform length and when resting on the bottoms of the sockets presenting electric lamps supported by their upper ends in a line conforming to and parallel with a line through the bottoms of the sockets.

3. A decorative lighting device comprising an elongated base having a bottom support-engaging surface and a row of spaced sockets open at the top of the base; tubular candle-like members insertable in said sockets and supported thereby perpendicular to the bottom of the base; lamp sockets carried by the upper ends of said members; and a plurality of wires interconnecting said lamp sockets in series, each wire being continuous and extending from one socket down through the tubular supporting member thereof, up through the next adjacent tubular member, and to the lamp socket carried thereby, and said wire having a free stretch between the two adjacent tubular members, the top of the base having a channel interconnecting adjacent sockets for the tubular members and adapted to receive and retain the free stretches of said connecting wires when the tubular members are inserted in their sockets and supported by the base in spaced relation.

4. A decorative lighting device comprising an elongated base having a bottom support-engaging surface and a row of spaced sockets open at the top of the base; tubular candle-like members insertable in said sockets and supported thereby perpendicular to the bottom of the base; lamp sockets carried by the upper ends of said members; a plurality of wires interconnecting said lamp sockets in

series, each wire being continuous and extending from one socket down through the tubular supporting member thereof, up through the next adjacent tubular member, and to the lamp socket carried thereby, and said wire having a free stretch between the two adjacent tubular members, the top of the base having a channel interconnecting adjacent sockets for the tubular members and 10 adapted to receive and retain the free stretches of said connecting wires when the tubular members are inserted in their sockets and supported by the base in spaced relation; and a return wire connected to the socket at 15 the one end of the base and extending to the other end of the base, said return wire being located in the channels interconnecting the adjacent sockets for the tubular members.

5. A decorative lighting device comprising 20 an elongated base having a bottom supporting surface and a row of spaced sockets open at the top of the base; tubular candle-like members insertable in said sockets and supported thereby perpendicular to the bottom of the base; lamp sockets carried by the upper ends of said members; a plurality of wires interconnecting said lamp sockets in series, each wire being continuous and extending from one socket down through the 25 tubular supporting member thereof, up through the next adjacent tubular member, and to the lamp socket carried thereby, and said wire having a free stretch between the two adjacent tubular members, the top of the 30 base having a channel interconnecting adjacent sockets for the tubular members and adapted to receive and retain the free stretches of said connecting wires when the tubular members are inserted in their sockets 35 and supported by the base in spaced relation; and a return wire connected to the socket at the one end of the base and extending to the other end of the base, said base having a channel in its bottom surface for receiving and 40 retaining said return wire.

6. A base for a decorative lighting device having a bottom-supporting surface adapted to rest directly upon a flat support, said base being elongated and provided with a row of 50 sockets extending longitudinally thereof and each open at the top of the base; and a wire-receiving groove in the top surface of the base extending between adjacent sockets and forming a conduit for the wire.

55 7. A decorative lighting device comprising a base having a bottom-supporting surface adapted to rest directly upon a flat support, said base being elongated and provided with a row of sockets extending longitudinally 60 thereof and each open at the top of the base; a wire-receiving groove in the top surface of the base extending between adjacent sockets; and a plurality of tubular members carrying at their upper ends lamp-sockets connecting 65 ed by wires and adapted to be inserted in

said sockets in the base after being wired together in series, the connecting wires being adapted to be received and retained by the wire-receiving grooves in the top surface of the base between adjacent sockets for the 70 tubular members.

Signed at Bridgeport, in the county of Fairfield, and State of Connecticut, this 11th day of April, 1931.
